INTERNAL COMBUSTION ENGINE

Victor F. Zahediakin, New York, N. Y.

Application June 25, 1935, Serial No. 28,325

2 Claims. (Cl. 123—90)

This invention relates to internal combustion engines and is particularly directed to improvements in the mechanism for actuating the valves thereof. Because of the fact that the metal parts expand when heated in the normal operation of the engine, it has been necessary to provide working clearance between the valves and the valve actuating mechanism to accommodate for this expansion. Naturally, when the clearance has not been taken up by expansion, as when the motor is cold or not heated to the normal operating temperature, it permits a great deal of vibration and impact, causing noise and damage to the parts.

It is therefore an object of this invention to provide an improved, simple, and efficient device incorporated in a valve actuating mechanism which provides for an ample amount of lost or idle motion for permitting expansion of the parts, which lost or idle motion is afforded in lieu of the usual clearance which not only permits expansion, but automatically maintains constant contact between the parts of the valve actuating mechanism whereby there is no impact or concussion such as would occur if complete clearance between the parts were taken up.

It is a further object of this invention to provide an improved device in the valve operating mechanism, which device permits expansion of the parts and results in operation of the valves without noise, vibration, or impact and without excessive wear or breakage of the contacting elements.

It is a still further object of this invention to provide a device for this purpose which is more easily manufactured, more positive, more durable, more accessible, and easier to install in the valve operating mechanism, also the invention in one phase, simply requires replacement of the cam follower normally used for a special cam follower incorporated in the improved device; and adds no additional reciprocating weight to the mechanism.

It is a still further object of this invention to provide a device of this character, quickly incorporated in the operating mechanism of the valve, which will permit operation of the engine valves in the event of failure or breakage of the device. It is also provided that by an adjustment in the event that the contact parts become worn, other available contact parts can be brought into operative position for replacement purposes.

It is a still further object of the invention to provide a device of this character which is effective for taking up the clearance by sliding or roll-

ing operation, thereby entirely eliminating impact and the usual springing or disalignment of the parts, the latter being an advantage particularly when the device is incorporated in the overhead type of engine valve employing a relatively long push-rod.

Other objects and certain advantages will be more fully apparent from the detailed description of the drawing, in which:

Figure 1 is a longitudinal sectional view with certain of the parts shown in elevation, this view showing the complete device incorporated in the operating mechanism;

Figure 2 is a side view of the adjusting screw incorporated in the device of Figure 1;

Figure 3 is a plan view of the lock nut used for locking the adjusting screw of the device shown in Figure 1;

Figure 4 is a side elevation of the upper cam element or take-up element in which the adjustable contact screw is mounted;

Figure 5 is a bottom view of the element of Figure 4;

Figure 6 is a view of one of the contact studs of the element shown in Figure 4;

Figure 7 is a side view of the main body of the cam follower incorporating the cam surfaces cooperating with the upper cam element;

Figure 8 is a top plan view of the element of Figure 7;

Figure 9 is a top plan view of the tension spring incorporated in the device of Figure 1 between the cam element and the cam follower body;

Figure 10 is a longitudinal sectional view of a cam follower incorporating a modified form of the device of this invention;

Figure 11 is a bottom view of the push-rod incorporated in the device of Figure 10;

Figure 12 is a side elevation partly in section of a modified form of device incorporated in the cam follower of the valve operating mechanism;

Figure 13 is a bottom view of the upper cam or wedge element of the device of Figure 12; and

Figure 14 is a top plan view of the body portion of the cam follower.

Referring to Figures 1 to 9 of the drawing, particularly Figure 1, a portion of the engine block is indicated at 15. The portion shown includes a valve seat and incorporates a valve guide element 16 in which a valve 17 is slidably mounted for operation in relation to the seat 18. A valve incorporated in the L-head type of engine is illustrated in this case. The valve has an abutment means 19 fixed on its lower end and a spring is 55

disposed under compression between the engine block and the abutment means.

The abutment means is attached in the following manner. An annular groove 20 is provided 5 near the end of the valve stem. A cup-shaped abutment disc 21 incorporating a radial abutment flange 22 at its lower edge is slidably mounted on the valve stem. In the assembly or mounting of the abutment plate, the halves of 10 a split collar 23 are placed within the annular groove fitting therein when placed together. The abutment disc 21 is then lowered about these split ring elements holding them in place in the annular groove, whereby they in turn prevent 15 downward displacement of the abutment plate or disc.

The cam shaft is shown at 24. One of the cams 25 thereof is shown in Figure 1, in operative contact with the cam follower unit 26. This cam 20 follower unit incorporates the take-up device of this invention. The follower unit is slidably mounted in axial alignment with the wave stem within a guide bore 27 of the engine body.

The main or body element 28 of the cam follower unit (see the detail views Figures 7 and 8) 25 has a flared lower end in operative contact with the cam and is in the form of a thimble. The take-up element or upper cam follower element 29 is slidably and rotatably mounted within the 30 bore of the cam follower. This take-up element is in the form of a sleeve including an integral nut or hexagonal head 30 at its upper end. An annular groove 31 is formed externally of the element just below the headed upper end to provide clearance for a wound spring 32 exerting 35 rotative force on the take-up element as will be hereinafter described.

It will be seen that when the take-up element 40 is telescoped in the cam follower body, a chamber is provided by the association of the annular groove with the bore of the body. The take-up element is internally screw-threaded and an adjustable contact screw 33 is entered thereinto, the upper contact or headed end of the screw 45 being in contact with the lower end of the valve stem at all times (see Figure 1). A lock nut 34 maintains the adjusting screw 33 in position relative to the take-up element 29.

The coil spring has one terminal anchored in a 50 radial slot 35 in the cam follower element and the other terminal anchored in a radial aperture in the take-up element toward the lower end of the annular groove and indicated at 35a. The spring is wound under considerable tension to 55 maintain a constant rotative force on the take-up element. This rotative force is converted into longitudinal or axial movement of the take-up element by a cam arrangement hereinafter disclosed.

60 Pins 36 having rounded lower ends are projected downwardly from the headed upper end of the take-up element surrounding the sleeve portion thereof. There are four of these pins spaced 90° apart. The upper edge of the cam follower body incorporates arcuate grooves 37 which may be generally described as having diametrically related centers. Therefore respective 65 diametrically related pins cooperate with these arcuate grooves. The result of the rotative movement constantly imparted to the take-up element is to urge the take-up element outwardly axially due to the fact that the pins ride up the curved 70 surfaces of the arcuate grooves.

The other pair of pins not in use or in direct 75 contact with the cam follower element are dis-

posed in diametrically cut slots 38 in the upper edge of the cam follower element. These slots present perpendicular end walls and afford positive abutments for engagement by the respective pins not in use for camming purposes.

At this point it will be recognized that in the event the pins which are actually in contact with the arcuate surfaces become worn, the take-up element can be rotated 90° to place the other pins in service for direct contact. In this event the 10 previously used pins can then function as the abutment pins since wearing of the contact or rounded ends thereof will not interfere with this latter function.

Now in the operation of adjusting the actuating 15 mechanism so that appropriate lost motion or idle movement is afforded, the take-up element is rotated against the tension of the spring so that the pins rest at the bottoms of the arcuate grooves. A gauge is then placed between the contact screw 33 and the bottom of the valve stem, and the contact screw is adjusted to the proper spacing. Upon release of the take-up element the spring will rotate and cam the same so that this clearance is taken up and positive contact 20 between the cam follower unit and the valve stem is maintained.

When the motor is cold the condition shown in the Figure 1 of the drawing will exist, that is to say, the pins will be high up on the arcuate surfaces. As the cam actuates the cam follower unit, the lost motion will be taken up with the pins moving to the bottom of the grooves for a cushioned operating contact. It will be seen that there can be no impact because these pins are 25 moving down a curved surface and no sudden abutment across a space occurs to cause impact or concussion. As the motor heats up and the parts expand, the take-up element will be rotated against the tension of the spring by an 30 axial force resulting from functioning of the parts axially moving down the curved surfaces as this progresses.

Now the spacing selected for the possible idle or lost motion is great enough to take care of any 40 expansion of parts, even under abnormal conditions, so that the valves cannot stay open and permit premature escape of gases.

The view (Figure 1) shows the position of the 45 elements of the unit when the cam is not acting to unseat the valve.

In the modification shown in Figures 10 and 11, a modified device operating on a somewhat similar principle is disclosed. In this case the improvements are applied to the overhead type of valve and for this reason the cam follower unit is shown in relation to a push-rod 40 operating 50 a rocker arm 41. It is not believed necessary to show the valve. A cam 42 engages the underside of the cam follower element 43 as in the usual practice.

The cam follower unit in this case as in the preceding form consists of two major parts, that is, a cam follower body 44 of thimble form. The take-up element 45 is also of sleeve form and is 55 nested or telescopically mounted in the cam follower body.

The solid or closed lower end of the take-up element presents an arcuate or curved upper surface 46. The push-rod 40 includes a ball portion 40a near its lower end contained within the take-up element and centering the push-rod relative thereto by virtue of a snug fit in the take-up element. An elongated diametrically disposed rib 48 forms an extension from the ball portion. 60

of the push-rod. The lower or cross edge 49 of this rib is rounded, but the rib itself is straight lengthwise along the lower edge and is disposed crosswise of the curved bottom of the take-up 5 element when in valve operating contact or working position.

A winding spring 50 is coiled about the push-rod, having one of its terminals anchored in a radial aperture 51 of the push-rod, and its other 10 terminal anchored in an aperture 52 in the upper edge of the take-up element. The push-rod therefore is under rotative pressure at all times so that when there is no working pressure axially of the cam follower and push-rod, rotative movement 15 of the push-rod takes place. This rotates the rib 48 relative to the arcuate surface. Thus the push-rod is elevated and the contact between the upper end of the push-rod and the rocker arm is constantly maintained.

20 Upon each valve operating movement the pressure applied longitudinally of the elements causes a camming action to ensue between the push-rod and the take-up element rotating these elements relatively until the rib reaches the bottom 25 of the arcuate surface to a position directly parallel therewith.

Another modified form of the invention is shown in Figures 12 to 14. The cam follower unit shown in the views illustrating this form is 30 placed in the mechanism in the same manner as the unit of Figure 1. The general elements of the unit are the same as in the preceding form, that is to say, a main cam follower body 63 and a take-up element 61 are related in the same 35 manner. A winding coil spring 62 is disposed in an annular recess 62a in the take-up element 61 in the same manner as in the preceding form for imparting rotative movement to the take-up element.

40 As shown, the take-up element incorporates an adjustable contact screw 63 as shown in the first form. A sleeve 64 is rigidly secured in an annular external groove 65 at the upper end of the cam follower body, this sleeve extending 45 above the upper end of the cam follower body. Motion limiting grooves 66 providing perpendicular abutment shoulders 67 are formed in the upper edge of the sleeve element and are diametrically related as to centers. A cam collar or 50 ring 68 is disposed around the take-up element and in assembled position is disposed within the sleeve immediately above the upper edge 69 of the cam follower body. This ring or collar is secured in position by radially disposed pins 70 which 55 project beyond the ring into the limiting grooves or slots. The pins provide the rotative abutment elements co-acting with the shoulders 67 for limiting rotative movement of the take-up element under the action of the spring.

60 Diametrically opposite portions of the upper edge of the cam follower element, as well as the adjacent portions of the lower edge of the ring, are provided with shallow grooves 71 providing arcuate cam surfaces or tracks. Balls 72 are in-

serted between and in contact with the adjacent grooves of the respective parts.

It will be apparent that the rotative forces of the spring will tend to spread the parts, that is to say, elongate the cam follower unit, maintaining the contact with the cam and with the lower end of the valve stem or the valve operating mechanism as the case may be. However, a limited amount of idle or free motion can occur, permitting expansion of the parts before solid 10 operating contact occurs. When the balls are located at the bottoms of the respective grooves, or the parts have been moved together until further motion is obstructed by the balls, positive driving contact occurs. It will be seen that this 15 occurs without concussion or impact since the balls move on curved surfaces and the lost motion is taken up gradually as opposed to impact, as when the parts move across a clearance.

These devices entirely eliminate clearance and 20 at the same time afford positive operating contact.

Having described my invention, I claim:

1. In a valve operating mechanism including a spring seated valve and a cam therefor, a cam follower unit in constant contact with the valve 25 and cam, said unit incorporating telescopically related elements, one in contact with the cam and the other in contact with the valve, a winding spring for urging said parts rotatively relative to each other, a cam surface and a groove having 30 vertical end walls formed on the end of one of said elements, pins projected from an adjacent surface of the other element, one of said pins riding on said cam surface and the other engaged in said groove, said elements moved apart under 35 the influence of the spring through the cam surface contact, said second pin limiting rotative motion by engagement with the vertical end walls of the groove, and said pins interchangeable as to the groove by rotative adjustment of the elements. 40

2. A device of the class described including a cam operated valve operating mechanism, comprising, an external shell forming the cam follower and having a closed end in engagement 45 with the cam, a cylindrical element axially slidably and rotatably mounted in said shell and including a head overhanging the upper edge of the external shell, said external shell and said head of said cylindrical element including cam 50 surfaces cooperating for causing relative axial movement upon relative rotation thereof, said shell and cylindrical element providing an annular chamber therebetween, said chamber located immediately adjacent the plane of the cam 55 surfaces, a coil spring disposed within said chamber and having its ends respectively attached to the external shell and the cylindrical element for urging said shell and cylindrical element rotatively in relation to each other, and an adjustable contact screw in said cylindrical element having its head extended axially outwardly therefrom. 60
